UNITED STATES PATENT OFFICE

2,279,171

DOOR OR WINDOW FRAME CONSTRUCTION

Clyde D. Lowry, Toledo, Ohio, assignor to Libbey-Owens-Ford Glass Company, Toledo, Ohio, a corporation of Ohio

Application December 30, 1939, Serial No. 311,898

5 Claims. (Cl. 189—76)

The present invention relates to door or window frames in general and more particularly to tubular metal frames such as are ordinarily used in show cases, poster cases, etc., although the invention is obviously not restricted to any specific use or uses.

Heretofore, it has been customary to fabricate door or window frames of this character of tubular metal sections which were welded together at the corners of the frame to provide an integral rigid construction. These tubular sections are preferably formed of extruded metal, such as aluminum, and it has been common practice to "Alumilite" the frame after the sections thereof are welded together whereby to provide a hard, durable surface as well as giving the frame a pleasing and attractive appearance. Briefly, the process of alumiliting consists in subjecting the extruded aluminum to a chemical and electrolytical action to form a surface film which is hard and shiny.

It has been found, however, that when the tubular sections forming the frame are welded together and then alumilited, the welded joints tend to darken, and this, I believe, is caused by the action of the electrolytical process on the metal. This may be due to the fact that those portions of the tubular sections which have been subjected to the welding action are physically different from those portions which have not been thus subjected, so that the alumiliting tends to adversely affect only the welded portions to cause a darkening thereof. In alumiliting the tubular metal frame, it is placed in a caustic bath and at times some of the material of the bath will find its way into the frame. As it is practically impossible to thoroughly flush out the tubular frame after alumiliting, the caustic material within the frame cannot be removed and the presence of this material also results in a corrosive action on the welded joints tending to weaken these joints.

It is the aim of this invention to overcome those objectional features set forth above in the fabrication of tubular frames of extruded metal. Briefly, this is accomplished by forming each section of the frame of two complemental inner and outer channel members which interfit with one another to give the desired tubular formation. The inner channel members of the frame are adapted to be welded together at the corners of said frame, while the outer channel members are not connected together, but instead are mitered at their adjacent ends and secured to the respective inner channel members. Due to the

fact that the outer channel members cover the inner channel members, the outer channel members only need be alumilited or otherwise surface finished, while the inner channel members can be made from raw or unfinished extruded stock. Further, since the outer channel members are not welded together, there is of course no reason for the mitered joints thereof to become darkened after the said channel members are alumilited.

10 Other objects and advantages of the invention will become more apparent during the course of the following description, when taken in connection with the accompanying drawing.

In the drawing, wherein like numerals are employed to designate like parts throughout the same:

Fig. 1 is a front view of a door or window frame constructed in accordance with the invention;

Fig. 2 is a transverse section therethrough taken substantially on line 2—2 of Fig. 1; and

Fig. 3 is a perspective sectional view showing the manner in which the frame is constructed and assembled.

Referring now to the drawing, the metal frame 25 shown in Fig. 1 is designated in its entirety by the numeral 5 and has mounted therein a sheet or pane of glass 6 by means of the metal sash construction 7. Although the metal frame 5 may be of any desired shape, it is herein shown as being

30 rectangular and composed of horizontal top and bottom sections 8 and 9 and opposite vertical side sections 10 and 11. Each of the sections of the frame is of tubular formation and consists of the complemental inner and outer channel members

35 12 and 13 which interfit one another as shown in Fig. 3. More specifically, the flanges 14 and 15 of the inner channel members 12 extend outwardly and are received between the inwardly directed flanges 16 and 17 of the outer channel

40 members 13. When the inner and outer channel members are interengaged with one another in this manner, they cooperate to form a tubular construction as illustrated in Fig. 2.

The adjacent ends of the inner channel members 45 12 are mitered at the corners of the frame as at 18, and these mitered ends are adapted to be welded together as indicated at 19. By welding the inner channel members of the several sections of the frame together, it will be apparent

50 that a strong, rigid construction will be provided. The outer channel members 13 constitute, in effect, a covering for the rigid frame composed of the inner channel members and, since the inner channel members are covered by the outer channel members, the said inner channel members

need not be alumilited or otherwise surface finished.

The outer channel members 13 are also mitered at their adjacent ends as at 20, but these mitered edges are not adapted to be welded or otherwise secured to one another. On the contrary, the outer channel members are independent of one another and are adapted to be secured to the respective inner channel members by screws or the like 21. With such a construction, the outer channel members may be alumilited or otherwise surface finished to present a pleasing and attractive appearance as well as to provide a hard, durable exterior surface. Since the outer channel members are not welded together, all danger of them becoming darkened along their mitered edges 20 after alumiliting is of course obviated. Likewise, the outer channel members can be thoroughly washed after alumiliting to remove all presence of caustic soda.

In assembling the frame 5, the adjacent mitered ends 18 of the inner channel members 12 are first welded together as at 19, after which the outer channel members 13 are fitted over the inner channel members as described above and secured thereto by the fastening screws 21. The metal sash construction 7 is then associated with the frame, and the pane of glass 6 mounted therein.

As best shown in Fig. 2, the metal sash construction 7 at the top, bottom, and sides of the frame comprises an outer member 22 and an inner member 23. The outer member 22 includes a front portion 24 extending substantially parallel with the pane of glass 6 and a base portion 25 extending rearwardly at right angles thereto and beyond the edge of the pane of glass. The base portion 25 is secured to the respective inner channel member 12 by screws 26. The front portion 24 of outer member 22 is provided along its inner edge with a bead 27 engaging the outer surface of the pane of glass and is further provided along its outer end with a forwardly directed flange 28 of any desired profile. This flange 28 not only forms an ornamental molding or edging but also serves to cover the slight space or gap between the outer flanges 15 and 17 of the inner and outer channel members 12 and 13 respectively. The base portion 25 of outer member 22 extends rearwardly a sufficient distance to cover the space or gap between the inner flanges 14 and 16 of the inner and outer channel members respectively. In other words, the flange 28 and base portion 25 extend transversely beyond the inner channel members and overlie the flanges 16 and 17 of the outer channel members so that the inner channel members are completely covered. Consequently, there is no need whatever for the surfaces of the inner channel members to be alumilited or otherwise finished.

The inner member 23 of the metal sash comprises a rear portion 29 provided along its inner edge with a bead 30 engaging the inner surface of the pane of glass 6 and at its outer end with a rearwardly turned base portion 31 which rests upon the base portion 25 of outer member 22 and is secured thereto by screws or the like 32. The base portion 31 of inner member 23 is preferably provided with transverse slots through which the screws 32 pass whereby the said inner member may be moved inwardly or outwardly to accommodate glass sheets of different thicknesses. When installing the pane of glass 6, the outer members 22 are first secured in place; the pane

of glass then positioned to engage the beads 27 of the outer members, after which the beads 30 of the inner members 23 are moved into contact with the inner surface of the glass and the screws 5 32 put in place and tightened.

In order to more rigidly secure the inner and outer channel members 12 and 13 together, the screws 26 may pass entirely through the base portions of the inner channel members and have 10 threaded thereon sleeves 33 in the opposite ends of which are threaded screws 34 passing through the base portions of the outer channel members. The screws 26 and 34 are oppositely threaded so that, upon tightening, the said screws will be 15 threaded into the opposite ends of the sleeves 33 to hold the channel members securely together as well as for securing the metal sash construction 7 to the inner channel members 12.

It is to be understood that the form of the 20 invention herewith shown and described is to be taken as the preferred embodiment of the same, and that various changes in the shape, size and arrangement of parts may be resorted to without departing from the spirit of the invention or the 25 scope of the subjoined claims.

I claim:

1. In a metal door or window frame of the character described, sections formed of inner and outer complemental metal channel members 30 interfitting one another to provide a tubular formation, means for securing the inner channel members together, while the outer channel members are independent of one another, and means for securing the outer channel members to the 35 respective inner channel members.

2. In a metal door or window frame of the character described, sections formed of inner and outer complemental metal channel members interfitting one another to provide a tubular 40 formation, said inner channel members having outwardly directed flanges, while said outer channel members have inwardly directed flanges overlapping and covering the flanges of the inner channel members, means for securing the 45 inner channel members together, while the outer channel members are independent of one another, and means for securing said outer channel members to the respective inner channel members.

3. In a metal door or window frame of the character described, sections formed of inner and outer complemental metal channel members interfitting one another to provide a tubular 55 formation, means for securing the inner channel members together, while the outer channel members are independent of one another, a metal sash construction carried by said inner channel members and adapted to hold a pane of glass, and means for securing said metal sash construction to the inner channel members and for also securing said outer channel members to said inner channel members.

4. In a metal door or window frame of the character described, sections formed of inner and outer complemental metal channel members 65 interfitting one another to provide a tubular formation, said inner channel members having outwardly directed flanges, while said outer channel members have inwardly directed flanges 70 overlapping and covering the flanges of the inner channel members, means for securing the inner channel members together, while the outer channel members are independent of one another, means for securing the outer channel members to the respective inner channel mem-

bers, and a metal sash construction carried by said inner channel members and adapted to hold a pane of glass, said metal sash construction covering the spaces or gaps between the said inner and outer channel members.

5. In a metal door or window frame of the character described, sections formed of inner and outer complementary metal channel members interfitting one another to provide a tubular formation, said inner channel members having outwardly directed flanges, while said outer channel members have inwardly directed flanges overlapping and covering the flanges of the inner

channel members, means for securing the inner channel members together, while the outer channel members are independent of one another, a metal sash construction carried by said inner channel members and adapted to hold a pane of glass, and means for securing said metal sash construction to the inner channel members and for also securing said outer channel members to said inner channel members, the said metal sash construction extending transversely beyond the inner channel members and overlying the flanges of the outer channel members.

CLYDE D. LOWRY.
